CONDENSER ASSEMBLY

Herman L. Hartzell, Anderson, Ind., assignor to
General Motors Corporation, Detroit, Mich., a
corporation of Delaware

Application November 15, 1937, Serial No. 174,521

7 Claims. (Cl. 175—41)

This invention relates to condensers and more particularly to that type of condenser used for ignition apparatus for internal combustion engines.

5 It has been discovered that the capacity of the condenser decreases with lower temperatures and the amount of decrease depends upon the type of material used in the condenser. In the construction of condensers used with ignition apparatus, the capacity will decrease approximately 15 percent when the temperature is lowered from 25° C. to —25° C. The result is that there is a lower capacity across the ignition contacts during cold weather than there is during 10 normal or hot weather. However, during cold weather with the lower coil resistance and higher battery voltage, the primary current is much higher than it is during warm weather so that a larger capacity is required if satisfactory point 15 operation is to be obtained.

An object of the present invention is to provide a condenser assembly which will provide extra capacity at low temperatures. This is accomplished by producing a condenser and thermostat arrangement in which the thermostat operates to connect an additional condenser unit in parallel with the main ignition condenser unit at low temperatures. This arrangement will allow the use of higher average primary current 20 without having excessive contact burning during cold weather. If the additional capacity were connected permanently in the circuit, excessive contact pitting would be the result during warm weather, thus the thermostat operates to disconnect the condenser from the circuit according to temperature conditions.

Another object of the present invention is to provide a condenser and thermostat assembly enclosed within a single case.

40 Further objects and advantages of the present invention will be apparent from the following description, reference being had to the accompanying drawing wherein a preferred embodiment of the present invention is clearly shown.

45 In the drawing:

Fig. 1 is a longitudinal sectional view, on an enlarged scale, of a form of condenser embodying the present invention.

Fig. 2 is a perspective view of several of the 50 parts of the thermostat, in separated relation, before assembly.

Fig. 3 is a perspective view of additional parts of the thermostat before assembly.

Fig. 4 is a modified form of the present invention taken on line 4—4 of Fig. 5.

Fig. 5 is a sectional view taken on the line 5—5 of Fig. 4.

Fig. 6 is a wiring diagram showing the elements of the condenser assembly, shown in Fig. 1, illustrating their relative position and circuit connections within the ignition system.

Fig. 7 is a wiring diagram showing the elements of the condenser assembly, shown in Fig. 4, together with an additional condenser illustrating their relative positions and circuit connections 10 within the ignition system.

With particular reference to Figs. 1, 2, and 3, 15 20 designates a tubular metallic can or casing having a closed end 21, which is provided with an opening 22. The casing 20 encloses a condenser assembly 25, and a thermostatic switch assembly 26.

The preferred form of the condenser assembly 25, shown in Fig. 1 comprises a condenser unit 30 wound into cylindrical form and separator 20 25 32 of insulating material. In the form disclosed in Fig. 1 the condenser units are formed by first winding insulating strips 34 and 35 of foil upon a tubular core 36 of insulating material. The strips of foil 34 and 35 are separated by layers 25 31 of insulating paper 37. After the condenser unit 30 has been wound into cylindrical form to the desired capacity several turns of insulating paper, namely the insulator 32, is wound about the unit 30 to provide a physical separation between the 30 condenser units 30 and 31. Upon completion of the winding of the separator the condenser unit 31, comprising insulated foils 34a and 35a, is wound upon the condenser assembly 30 until the condenser assembly 31 is completed to the desired capacity. It will be noted that the foil margins 34 and 34a project beyond the margins of the insulation 36 at the thermostat end of the condenser, and the foil margins 35 and 35a project beyond the insulation at the terminal 40 end of condenser.

As is well known to makers of this type of condenser, the side margins of foil strips may be readily crushed together to form a mass of foil metal at each end of the condenser units to 45 provide means for attaching connectors or conductors to the foils. In the form shown in Fig. 1, a conductor cable 40 having a bared end 41 is soldered to the crushed foil ends 35 and 35a of the units 30 and 31.

50 Associated with the condenser units 30 and 31 is the thermostatic switch device 26. The switch itself comprises a base 50 of insulating material, and as shown the outer face 51 of the support, see Fig. 2, is provided with a plurality of bosses 55

or projections 52 and a recess 53 while the opposite or inner face 54 of the support, see Fig. 3 is provided with a raised portion 55 of non-circular contour. An internally threaded insert 56 is embedded in the support and is provided with a flange 57 which extends beyond the inner face 54 of the support 50. Supported on the inner face 54 of the support is a cup-shaped member 58. This member is provided with a non-circular opening 59 to receive the projection or raised portion 55 which projection operates to prevent the cup-shaped member from turning relative to the support. The cup-shaped member is also provided with an apertured ear 60. As illustrated in Fig. 3, it is preferred that the ear be formed integral with the member 58 and this is accomplished by stamping the ear 60 from the side wall of the member 58. In order to maintain the cup-shaped member to the support the apertured ear is fitted over the flange portion 57 of the insert 56 which is spun over the ear. An insulating disc 61 and a ground strap 62 are secured on the raised portion and within the cupportion of the member 58 by rivets 63. These rivets also secure a bi-metallic member 64 and a U-shaped ground strap 65, which straddles the bi-member 64, to the outer face of the support. The yoke portion of the strap 65 is deformed as at 66 and adapted to extend into the opening 21 and contact the casing 20.

The free end of the bi-metallic member 64 carries a movable contact 67 and said member is so constructed that it normally maintains the contact 67 out of engagement with a relative stationary contact 66 during normal or hot temperatures. The relative stationary contact has screw threaded engagement with the insert 56 so that it may be adjusted to suit the various climatic sections to which it is subjected.

In assembling the thermostatic switch device 26 and condenser assembly 25, the thermostatic switch device 26 is first placed into the case 20 so that the detent 66 of the ground strap 65 will extend into the opening 22 in the bottom wall 21. Then the condenser assembly comprising the units 30 and 31, is placed therein. It will be noted that the end of the separator 32 adjacent the thermostatic switch device 26 extends beyond the margins of foil 34 and the ground strap 62 and bears against the insulating disc 60 so as to insulate the margins 34a of condenser 31. The conductor 40 is threaded through suitable apertures of an insulating disc 70, a resilient metal washer 71, and through a neck portion 72 of a cover 13. The cover is also provided with a peripheral flange which fits snugly within the interior of the case 20. The cover is forced toward the condenser form with substantial pressure sufficient to cause the margins 34b of foil 34 to bear against the strap 62, the foil margins 35b against a peripheral flange 75 provided by the cup-shaped member 58 and the detent 66 against the bottom 21 to form good electrical connections between the parts. The bosses 52 provided on the base engage the bottom 21 to prevent the yoke 65 from collapsing and also prevent movable contact 67 from being forced into engagement with the contact 66. While this pressure is applied to the condenser cover 73 the end margin 76 of the case is spun over the flange 74 in order to retain the cover in position and the condenser margins 34b and 35b firmly against the strap 62 and flange 75, respectively, and prevent endwise movement of the elements within the case. The

neck portion 72 is deformed as at 77 to grip the insulation of the conductor and provide a moisture seal between the cover and the cable. The aperture 21 is filled with solder 78 so to form a seal for the bottom 21 and also assists in maintaining a good ground connection between the ground member 65 and the case 20.

In the modified form of the present invention, shown in Figs. 4 and 5, the casing 120 is adapted to receive a thermostatic switch device 126 and a condenser body 125. In this instance the condenser body 125 is wound into cylindrical form by winding insulated strips 134 and 135 of foil upon a tubular core 136. The layers of foil are separated by insulating paper 137 with the foil 134 margins 134a and 135a respectively extending beyond opposite side margins of the paper 36.

The thermostatic device 126 comprises a support 140 with a leg 141. The leg is deformed to provide a projection 142 which is adapted to fit into the aperture 121 of the case 120. An ear 143 formed integral with the leg 141 and is bent at an angle and supports an adjustable contact 144. A bi-metallic member 145 and an L-shaped bracket 146 are insulatingly supported upon the support 140, as clearly shown in Fig. 5, but the bi-metallic member 145 and the bracket 146 are electrically connected to each other.

A conductor 150 having a bared end is soldered to the margins of foil 135 as indicated at 152. The bracket 146 comprises leg portions 153 and 154. The leg portion 153 is formed so as to support one end of the condenser body 125.

A strap or connector 155 preferably has one end thereof soldered to the leg portion 154 and the other end is soldered to the margins of foil 134. A movable contact 156 is carried by the free end of the bi-metallic member 145. This contact is normally separated from the relative stationary contact by the bi-metallic member 145 during warm weather, but the member 145 is adapted to flex upwardly, as viewed from Fig. 4, from its normal position in cold weather so that the movable contact 156 will engage the contact 144 to ground the foil 134 through elements 155, 146, 145, 156, 144, 140 and 20.

In assembling the condenser, shown in Fig. 4 and Fig. 5, the thermostatic switch 126 is so positioned that the projection 142 will extend into the aperture 121 and in contact with the casing 120. Then the cable 150 is threaded through an aperture of an insulated disc 160 and through a hollow boss provided by cover 161, after which the cover is forced into the case 20 with substantial pressure sufficient to cause the margins 134a of foil 134 to be crushed against the strap connector 155 and the leg 154 to provide a good electrical connection for the foil 134. While this pressure is applied to the condenser cover 161 the end margin 162 of the case is spun over the cover to retain the cover in position and prevent the thermostatic switch and condenser assemblies against longitudinal movements within the case.

Referring to Fig. 6 the dash line 20 represents the casing of the condenser assembly 25 shown in Fig. 1. The casing operates as a conductor or terminal for the condenser units 30 and 31 to ground the condenser as at 201, while the lead 40 may be connected to a lead or conductor 202 joining a circuit breaker 203 within the primary of an ignition coil 204 that eventually connects a conductor 205 to connect a battery 206 grounded at 207. In Fig. 7 the dash line 120

represents the casing of the condenser assembly shown in Fig. 4 while dash lines 250 represents a second condenser employed in the ignition system.

5 While the embodiment of the present invention as herein disclosed, constitutes a preferred form, it is to be understood that other forms might be adopted, all coming within the scope of the claims which follow.

10 What is claimed is as follows:

1. A condenser assembly for an ignition system comprising in combination; a metallic case; a condenser body comprising foils and insulating strips; a conductor electrically connected to one

15 of the foils; a support provided with a fixed contact; means for connecting the other foil with the fixed contact; a thermostatic strip anchored to the support and arranged to flex in response to temperature changes; a contact carried by the free end of the strip and normally held out of engagement with the fixed contact; and means for connecting the strip with the case so that the second mentioned foil will be grounded upon closure of the contacts.

20 2. In a condenser assembly for an ignition system the combination comprising; a metallic case; a condenser body including windings of foils and insulating strips, the side margins of the foils projecting respectively beyond the side margins of the insulating strips; a conductor connected to one of the foil margins; a base provided with a stationary contact; means for connecting the other foil margin with the stationary contact; a thermostatic strip anchored to the base and capable of bending in response to low temperatures; a contact carried by the free end of the strip and normally held out of engagement with the stationary contact; and means for connecting the strip with the case for grounding the second mentioned foil margins upon closure of the contacts.

25 3. In a condenser assembly for an ignition system the combination comprising; a metallic case; a condenser body including windings of foils and insulating strips, the side margins of the foils projecting respectively beyond the side margins of the insulating strips; a conductor connected to one of the foil margins; a base supporting an adjustable contact, means for connecting the other foil margin with the adjustable contact; a bi-metallic strip secured at one end to the base and capable of bending in response to change of temperature; a contact carried by the strip and normally held out of engagement with the adjustable contact; and a conductor connected to the strip and the case to ground the second mentioned foil margin upon closure of the contacts.

40 4. A condenser assembly for an ignition system comprising in combination; a metallic case having a closed end; a condenser body comprising windings of foils and insulating strips the side

margins of the foils projecting beyond the side margins of the insulating strips; a conductor connected to one of the foil margins; a base supporting a normally stationary contact; a plate associated with the stationary contact and connected with the other foil; a movable contact; a thermostatic element carrying the movable contact and normally holding same spaced from the stationary contact and capable of bending at low temperature to close the contacts; and a grounding strap connecting the thermostatic element with the closed end of the case whereby the second mentioned foil will be grounded upon closure of the contacts.

45 5. A condenser assembly comprising in combination; a tubular metallic casing having a closed end; a condenser foil assembly including a body of windings of foils and insulating strips, the side margins of the foils projecting respectively beyond the side margins of the insulating strips; a conductor electrically connected to one of the foils; a support; an adjustable contact carried by the support; a thermostatic element and a grounding member secured together at one of their ends to the support, a movable contact carried by the thermostat and normally out of engagement with the stationary contact, but said element capable of bending at low temperature to close the contacts so as to ground the other foil, a cover for the open end of the casing and having an aperture through which the conductor passes; and means for securing the cover and for clamping the second mentioned foil margins against the adjustable contact and for urging the other end of ground member against the closed end of the case.

50 6. A condenser assembly for an ignition system comprising, in combination; a metallic case; a condenser body comprising separate units of foils and insulating strips; supported within the case; a conductor electrically connected to one of the foils of each unit; means for connecting the other foil of one unit with the case; normally separated contacts located within the case one of which is movable; means for connecting the other foil of the second unit with one of the contacts; and a bi-metallic member for connecting the other contact with the case, said bi-metallic member operable at a low temperature to close the contacts whereby the other foil of the second mentioned unit is grounded to the case.

55 7. A condenser assembly comprising in combination; a condenser body comprising separate units of foils and insulating strips; a conductor electrically connected to one foil of each unit; means for connecting positively the other foil of one unit to ground; a stationary contact; a thermo responsive contact; means for connecting one of the contacts to ground; and means for connecting the other contact with the other foil of the second unit.
